(57) **CLAIM**

The ornamental designs for a single screen television with transparent sides and back, as shown and described.

DESCRIPTION

The present specification cross-references U.S. Design application Ser. No. 29/499,278 for Four Screen Television, filed concurrently with the Design Patent Application.

FIG. 1 is a top view.

FIG. 2 is a front view.

FIG. 3 is an isometric view.

FIG. 4 is a left side view.

FIG. 5 is a rear view; and,

FIG. 6 is a right view.

1 Claim, 6 Drawing Sheets
